PATENT LAW GROUP: Atkins and Associates, P.C.

(57) **CLAIM**

The ornamental design for a guitar body, as shown and described.

DESCRIPTION

FIG. 1 is a perspective view of a guitar body showing our new design;

FIG. 2 is a front view thereof;

FIG. 3 is a rear view thereof;

FIG. 4 is a left side view thereof;

FIG. 5 is a bottom view thereof;

FIG. 6 is a right side view thereof;

FIG. 7 is a top view thereof;

FIG. 8 is a cross-sectional view thereof, shown in the environment of an entire guitar;

FIG. 9 is another perspective view thereof;

FIG. 10 is another front view thereof;

FIG. 11 is another rear view thereof;

FIG. 12 is another right side view thereof; and,

FIG. 13 is another left side view thereof.

The broken lines represent the portions of the guitar body and its environment, which form no part of the claimed design.

1 Claim, 8 Drawing Sheets
